US0D1096784S

(12) **United States Design Patent** (10) Patent No.: **US D1,096,784 S**
(45) Date of Patent: ** Oct. 7, 2025

(54) **DISPLAY OR PORTION THEREOF WITH
GRAPHICAL USER INTERFACE**

(71) Applicant: **Apple Inc.**, Cupertino, CA (US)

(72) Inventor: **Graham R. Clarke**, Scotts Valley, CA (US)

(73) Assignee: **Apple Inc.**, Cupertino, CA (US)

(**) Term: **15 Years**

(21) Appl. No.: **29/908,063**

(22) Filed: **Jan. 11, 2024**

Related U.S. Application Data

(63) Continuation of application No. 29/787,300, filed on Jun. 5, 2021, now Pat. No. Des. 1,015,341.

(51) LOC (15) Cl. **14-04**

(52) U.S. Cl.

USPC **D14/486**; D14/488

(58) **Field of Classification Search**

USPC D14/485-495

CPC G06F 3/048-04897

See application file for complete search history.

(57) **CLAIM**

The ornamental design for a display or portion thereof with graphical user interface as shown and described.

DESCRIPTION

The FIGURE is a front view of a display or portion thereof with graphical user interface showing the claimed design. The outer broken lines in the FIGURE show a display or portion thereof, and form no part of the claimed design. The other broken lines in the FIGURE show portions of the graphical user interface that form no part of the claimed design.

1 Claim, 1 Drawing Sheet
